UNITED STATES PATENT OFFICE.

JOHN DOYLE, OF HOBOKEN, NEW JERSEY.

RUG-HOLDER.

1,275,875.

Specification of Letters Patent. Patented Aug. 13, 1918.

Application filed March 13, 1918. Serial No. 222,190.

To all whom it may concern:

Be it known that I, JOHN DOYLE, a citizen of the United States, residing at Hoboken, in the county of Hudson and State of New Jersey, have invented a certain new and useful Improvement in Rug-Holders, of which the following is a specification.

The invention relates to fastening means adapted to engage the margin of a rug, carpet, or other analogous floor covering and hold it to the floor, and the object of the invention is to provide a fastener which shall be inexpensive, easily and quickly engaged with the rug on the under face thereof, and be easily and reliably secured to the floor, lie concealed in the fabric of the rug, and also be easily disengaged when required.

The invention consists in certain details of construction and arrangement, by which the above objects are attained, to be herein-after described and claimed.

The accompanying drawings form a part of this specification and show the invention as it has been carried out in practice.

Figure 1 is a perspective view of the improved fastener.

Fig. 2 is a side view of the same.

Fig. 3 is a vertical central section.

Fig. 4 is a plan view.

Fig. 5 is a view of the under face of the fastener.

Fig. 6 is a front elevation.

Figs. 7, 8, 9, 10 and 11 show the fastener in side elevation in several successive stages in the operation of engaging the rug and securing the fastener and rug to the floor.

Fig. 12 is a top view of a portion of a rug thus secured.

Similar letters of reference indicate the same parts in all the figures.

A is a triangular plate of sheet metal, preferably thin steel, having a perforation at approximately the center in which is received the shank B of a track, serving as a spur projecting on the under face, thrust through from above and held by soldering the head B¹ thereof to the upper face of the plate.

Between the tack B and one edge of the plate is another perforation on the center line, through which a pin C is thrust from below and held by soldering an arm C¹ of the pin upon the under face of the plate. The arm C¹ is formed by bending the wire of the pin at a right angle and it lies prefer-

ably at a right angle to the adjacent edge of the plate. The pin is curved and extends outwardly on the center line with the point C² projecting outwardly and downwardly a little distance from such edge.

The pin is preferably of pliable wire so that its curve may be flattened and embedded in the rug when the spur is driven into the floor.

In engaging the fastener with the rug M the margin of the latter is raised and turned back and the under face of the plate applied upon the under face of the rug with the edge of the latter against the spur B, as in Fig. 7, and the curved pin C extended toward the body of the rug, the tack serving as a gage to locate the fastener relatively to the edge of the rug. The point C² of the pin is then thrust through the rug by folding the plate upon the under face of the latter, see Fig. 8, and a continuation of such movement brings the upper face of the plate against the under face of the rug, with the pin extending in an arch therethrough, and with its point C² embedded therein, as in Fig. 9. The margin of the rug is then laid upon the floor with the spur in position to be driven, see Fig. 10, and by blows of a hammer, or the application of sufficient force through a plane surface laid upon the upper face of the rug above the plate, the tack or spur is driven into the floor and thus holds the rug. The same driving implement flattens the arch of the curved pin and conceals or partially conceals it in the material of the rug, as in Fig. 11. The point C² of the pin may enter the floor as shown in Fig. 11, and aid in holding down the extreme edge of the rug, or may be simply bent down, but in either case it projects downwardly and is effectively sheathed and concealed. As many fasteners as are necessary may be thus applied along the margin of the rug, the spurs serving to locate them at the same distance from the edge.

It will be noted by referring to Fig. 11, that the entire under face of the plate A does not lie in close contact with the floor but is elevated at one edge by the arm C¹ of the pin thus providing a crevice for the introduction of a suitable tool, preferably a bifurcated claw adapted to extend beneath the plate on both sides of the arm C¹, by which the plate with its spur or tack may be lifted and the latter withdrawn from the

floor. A reversal of the engaging operation draws out the pin and releases the fastener.

I claim:—

- 5 1. The rug holder described comprising a plate, a tack secured to said plate and projecting downwardly from the under face thereof and adapted to be driven into a floor, a perforation in said plate between 10 said tack and an adjacent edge of said plate, a curved pin thrust through such perforation from the under face of said plate, said pin extending upwardly from the upper face of 15 said plate and thence outwardly at a right angle to such edge and beyond the latter and terminating in a downwardly projected point adapted to penetrate and engage a rug, and an arm on said pin secured to and projecting upon such lower face and serving 20 to attach said pin to said plate and to hold such edge of said plate out of contact with the floor.
2. The rug holder described comprising a plate having a perforation, a tack thrust

through such perforation from the upper 25 face of said plate and having a head secured to such upper face, a second perforation in said plate between said tack and an adjacent edge of said plate, a curved pin thrust through said second perforation from 30 the under face of said plate and having an arm secured to such under face, said pin extending upwardly from such upper face and thence outwardly at a right angle to and beyond such edge and terminating in a 35 downwardly projected point adapted to penetrate and engage a rug, said tack adapted to serve the double function of holding said plate to a floor and as a gage in locating the point of engagement of said pin with 40 such rug, and said arm adapted to serve the double function of securing said pin to said plate and holding said edge out of contact with the floor.

In testimony that I claim the invention 45 above set forth I affix my signature.

JOHN DOYLE.
